(57) **CLAIM**

The ornamental design for a beverage container lid, as shown and described.

DESCRIPTION

FIG. 1 is a top perspective view of a beverage container lid showing my new design;

FIG. 2 is a front view thereof;

FIG. 3 is a rear view thereof;

FIG. 4 is a right side view thereof;

FIG. 5 is a left side view thereof;

FIG. 6 is a top view of thereof; and,

FIG. 7 is a bottom view thereof.

In FIG. 7 the innermost solid line forms the boundary of the claim. The broken lines and unshaded areas depict portions of the beverage container lid that form no part of the claimed design.

1 Claim, 3 Drawing Sheets
